Inventor
Samuel Bucksbaum
by Zabel and Mueller Atlys.

UNITED STATES PATENT OFFICE.

SAMUEL BUCHSBAUM, OF CHICAGO, ILLINOIS.

CALIPERING DEVICE.

1,413,319.

Specification of Letters Patent. Patented Apr. 18, 1922.

Application filed July 5, 1918. Serial No. 243,330.

To all whom it may concern:

Be it known that I, SAMUEL BUCHSBAUM, a citizen of the United States, residing at Chicago, in the county of Cook and State 5 of Illinois, have invented a certain new and useful Improvement in Caliper Devices, of which the following is a full, clear, concise, and exact description, reference being had to the accompanying drawings, forming 10 a part of this specification.

My invention relates to caliper or measuring devices and has for its object the provision of an improved device of this character which can be used for a plurality 15 of purposes.

In the particular form in which the invention is disclosed herein it is applicable for the measurement of fingers to ascertain the correct ring therefor. The same mechanism 20 is equally applicable for the measurement of precious stones, and also has other measuring facilities.

This particular form of the invention I will now describe in connection with the accompanying drawing illustrating the same, in which—

Fig. 1 is a top view of a device constructed in accordance with my invention;

Fig. 2 is a view looking at the opposite 30 side thereof, and

Fig. 3 is a side view thereof.

My improved device consists of a solid plate 10 having the slot 11 therethrough. A slide 12 surrounds three sides of the device 35 and is slidable there along, being confined to a rectilinear movement by means of the rivets 13, which rivets at the same time keep the slide in its proper shape. The slide also has a finger or thumb piece 14 so that it may 40 be more readily grasped and slid along the plate 10. The slide also has a pointer 15 on one side thereof which co-operates with suitable graduations 16 which represent ring sizes of the American standard type. An 45 expandible and collapsible spring 17 has its extremity 18 firmly fastened in the slide 12. This spring is slidably guided under two clasps 19, is then formed into a loop 20, and is firmly held near its free extremity by 50 the clasp 21. As the slide 12 is moved from right to left or vice versa, the loop 20 becomes enlarged or restricted, as the case may be, thus providing a larger or smaller circular opening. In this manner the loop is 55 adjusted to the finger and the pointer 15 indicates in connection with the scale 16

the actual size of the loop in terms of the American standard ring sizes.

The left hand extremity of the plate 10, as shown in Fig. 1, fixedly carries the shell 60 22 which extends around three sides of the plate 10 and which in part consists of the guides or clasps 19 through which the spring 17 is slidable. The shell 22 also has a band 65 23 which forms the clasp 21 to tightly hold one extremity of the spring in position, this band being continued over the other side of the shell where in connection with the shell it is firmly fastened to the plate 10 by the rivets 24.

The face of the plate 10 shown in Fig. 1 also is provided with millimeter graduations 25 which extend from a straight edge 26, preferably extending upwardly from the shell 22. This straight edge 26 in connection with the thumb piece 14 provides abutments between which stones or other articles may be suitably measured in connection with the measuring scale 25. One edge of the plate 10 is also provided with graduations in inches, as shown at 27, so that further measurement may be made in connection with which the slide 12 may cooperate.

The spring 20 has an extending finger 28 85 which holds out the side of the loop so as to keep the loop in a normally rounded condition.

From what has been thus described the nature of my invention will be readily clear 90 to those skilled in the art.

Having thus described one form which my invention may take, what I claim as new and desire to secure by Letters Patent is:

1. A device of the character described 95 comprising a slotted support, a slide movable on the support, means passing through the slot in said support for securing the slide to the support, a thumb piece on the slide, a shell carried by the support and 100 having a straight edge formed thereon, a scale on the support with its zero point at said straight edge, and a dilatable and contractile spring secured adjacent one of its ends to said support and having its other 105 end attached to the slide, said shell having means formed thereon to guide said spring as it is moved by said slide.

2. A device of the character described 110 comprising a support, a slide movable on the support, means for securing the slide to the support, a thumb piece on the slide, said

support having a straight edge formed thereon, a scale on the support with its zero point at said straight edge, a second scale on said support, and a dilatable and contractible spring forming a loop of variable size secured adjacent one of its ends to said support and having its other end attached to the slide, said slide having a straight

edge on said support to measure the thickness of objects placed between said straight edge portions, and having an extension thereon cooperating with said second scale to indicate the size of said loop.

In witness whereof, I hereunto subscribe my name this 27th day of June, A. D. 1918.

SAMUEL BUCHSBAUM.
